UNITED STATES PATENT OFFICE.

MARY FOOTE HENDERSON, OF ST. LOUIS, MISSOURI.

MOVEMENT-CURE MACHINE.

SPECIFICATION forming part of Letters Patent No. 398,255, dated February 19, 1889.

Application filed November 17, 1888. Serial No. 291,101. (No model.)

To all whom it may concern:

Be it known that I, MARY FOOTE HENDERSON, of St. Louis, in the State of Missouri, have invented a new and useful Improvement 5 in Movement-Cure Apparatus, which improvement is fully set forth in the following specification.

This invention has reference to a class of apparatus for practicing the so-called "Swedish movement-cure," and is designed to substitute automatic mechanical movements for manual treatment or manipulations in producing such actions as rubbing, kneading, beating, &c. The general effect of this kind 10 of treatment is to stimulate the circulation of the blood in the parts of the body to which the treatment is applied. It is usually administered by skilled manipulators; but the expense attending it places it beyond the means 15 of many people who might be greatly benefitted thereby, and, moreover, most of the movements can be more effectively performed by mechanical means. The same objection applies to most of the mechanical contrivances heretofore designed to do the work of the skilled operator, such contrivances being 20 costly, complicated, and requiring a large space for their proper operation.

The object of this invention is to supply a 25 simple and portable apparatus that can be cheaply made and easily manipulated, and by means of which the peculiar quick vibratory motion can be produced and communicated by a ball, rubber, brush, agitator, or other 30 special attachment or appliance to the part of the body requiring friction, irritation, agitation, or like treatment.

In carrying out my invention I provide a 35 suitable frame, which may be of wood, in which is mounted a rock-shaft having a socket for inserting a rubber, stirrup, or other attachment. This shaft may be termed the "vibrator," and mechanism is provided for imparting to it the peculiar motion above alluded to. The main shaft, which has a handle 40 for rotating it, carries a large friction-wheel, which imparts a rapid motion to a small friction-wheel in contact therewith, and from which the vibrator-shaft is oscillated through a connection-rod and crank-arm, the connec-

tion-rod being adjustable lengthwise of said crank-arm, so as to regulate the extent of motion of the vibrator. The shaft of the small friction-wheel is journaled in brackets adjustable in the frame toward and away 55 from the large friction-wheel.

In the accompanying drawings, which form part of this specification, Figure I is a side elevation of an apparatus constructed in accordance with the invention; Fig. II, an end 60 elevation thereof; Fig. III, a detail in sectional elevation, and Fig. IV a view of one of the attachments.

The frame consists of the base A and the side uprights, B, extending lengthwise of the 65 base. The main shaft C is supported in bearings at the middle part of uprights B and near the top thereof. This shaft carries a large friction-gear, D, which gears with the small friction-wheel E on shaft F at the right-hand end, Fig. I, of the frame. To insure 70 good frictional contact, the peripheries of the wheels D and E may be grooved, as shown, and to prevent noise the latter is preferably made of leather or like material. At the left 75 end of the frame is the vibrator-shaft G, provided with a socket for the reception of the shank h of a rubber or other attachment, which is held in the socket by a set-screw, b.

On one end of shaft F is a disk, f, provided 80 with a crank-pin, g, upon which is pivoted one end of connection-rod I. The other end of this rod is pivoted to an arm, K, secured to vibrator-shaft G, so that the rotation of crank-shaft F imparts to the vibrator-shaft a 85 rapid oscillating motion.

For some purposes—such as shaking or agitating a limb—it is desirable to give to the shaft G a comparatively large movement, while for other purposes—such as rubbing the skin 90 on the face or any sensitive part—a very slight oscillation is desired. In order to obtain the necessary range of motions, the connection of rod I with arm K is adjustable lengthwise of the latter. As shown, rod I is pivoted on a 95 pin, i, one end of which passes through a slot, k, in arm K, and it can be clamped at any point in said slot by the thumb-screw l. To increase or diminish the amplitude of motion of the vibrator, the thumb-screw l is loosened 100

and the pin *i* moved in slot *k* farther from or nearer to shaft *G*, and then clamped in place.

For some treatment far greater power is required than for others, and on this account it

- 5 is desirable to regulate the contact of friction-gears *D E*, for if considerable resistance is put upon the vibrator-shaft there is likelihood of the friction-wheels slipping, whereas for lighter work it is of course desirable that
- 10 the pressure of one of these wheels upon the other be comparatively light. In view of this the crank-shaft *F* has its bearings in swinging brackets *M*, (one of which is shown in Fig. III), hung by screws *m* from uprights *B*. If
- 15 it be found that, owing to resistance upon the agitator-shaft, the friction-gears have a tendency to slip, they can be pressed tighter together by the set-screws *N*, which screw into the ends of uprights *B*, and are in contact at
- 20 their inner ends with the swinging bearings *M*.

It will be understood that any number of attachments may be furnished with the machine for utilizing the motions of the agitator for different specific purposes.

- 25 The attachment *H* (shown in Figs. I and II) is a ball covered with kid or other smooth material for application to the face or scalp. A rougher surface may be used if greater irritation be required. The attachment *O* (shown
- 30 in Fig. IV) is a stirrup faced with a sheet of rubber, *o*, in which the arm or foot can be placed to agitate the limb.

Of course power can be communicated to the main shaft in any way. As shown, a

- 35 crank-handle, *P*, is provided for this purpose.
- The use of the large and small friction-wheels *D E* converts the comparatively-slow rotation of shaft *C* into a very rapid rotation of the crank-shaft, and gives to the vibrator
- 40 the peculiar rapid vibratory motion essential for the proper performance of its functions, while the arrangement of the large wheel in

the middle, and the crank and vibrator shafts, respectively, on each side thereof, gives compactness, which is essential to a portable machine, and steadiness in operation.

Having now fully described my said invention, what I claim, and desire to secure by Letters Patent, is—

1. In a movement-cure apparatus, the combination of the large and small friction-wheels and their respective shafts, the vibrator having a socket for the insertion of a rubber or other attachment, and a connection-rod for imparting a rapid oscillation to said vibrator, substantially as described.

2. The combination, with the vibrator and main shaft, of means, including a large and small friction-wheel, for transmitting motion from the latter to the former, the shaft of one of said friction-wheels having bearings adjustable toward and away from the other friction-wheel, substantially as described.

3. In a movement-cure apparatus, the combination of a portable supporting-frame, a main shaft having bearings at the middle part of the frame and carrying a large friction-wheel, a crank-shaft carrying a small friction-wheel engaging the large wheel, said crank-shaft having bearings in adjustable brackets, adjusting-screws for said brackets, a vibrator-shaft, a connection-rod for communicating motion thereto from said crank-shaft, and an adjustable connection between the end of said rod and an arm secured to said vibrator-shaft, substantially as described.

In testimony whereof I have signed this specification in the presence of two subscribing witnesses.

MARY FOOTE HENDERSON.
